I claim the ornamental design for an umbrella stand, as shown and described.

DESCRIPTION

FIG. 1. Is a front perspective view of my umbrella stand;

FIG. 2. Is a rear view thereof;

FIG. 3. Is a right view thereof;

FIG. 4. Is a left side view thereof;

FIG. 5. Is a top view thereof;

FIG. 6. Is a bottom view thereof; and,

FIG. 7. Is an alternate embodiment of FIG. 1.

The broken line portions of the disclosure are for illustrative purposes only and form no part of the claimed design.
